UNITED STATES PATENT OFFICE.

ALEXANDER D. ELLIOTT, OF VIOLA, ILLINOIS.

CONVERTIBLE FURNITURE.

1,286,832.

Specification of Letters Patent.

Patented Dec. 3, 1913.

Application filed March 4, 1915. Serial No. 11,933.

To all whom it may concern:

Be it known that I, ALEXANDER D. ELLIOTT, a citizen of the United States, residing at Viola, in the county of Mercer and State of Illinois, have invented certain new and useful Improvements in Convertible Furniture, of which the following is a specification.

My invention relates to that class of furniture in which a stationary member forms a support for a swinging member and the two together when in folded position form a chair or settee but when unfolded and extended form a bedstead or support for a mattress in horizontal position. My invention is in the nature of an improvement upon the convertible furniture disclosed in my Patent No. 1,120,701, granted December 15, 1914. In that instrument I show and describe a convertible piece of furniture which comprises a generally L-shaped frame comprising side members and cross members securing the side members together, to which frame is pivotally attached at its lower forward edge a swinging frame which when swung downward away from the fixed frame forms a partial support for a mattress. To the rear end of the swinging frame in said patent is connected an intermediate member also forming a partial support for the mattress and to the rear edge of the intermediate frame is pivoted a bodily movable frame which when the furniture is folded or collapsed moves upwardly into a substantially vertical position, the mattress, if any, on the bed being folded intermediate its ends and supported within the back of the chair or settee.

My invention is in the nature of an improvement upon the furniture of said prior patent and comprises a number of features among which may be stated that the seat proper is so attached to the swinging frame that when the latter is opened out or extended the seat member which comprises also the arms swings forward beneath the end or foot of the bed to form a support therefor. Another feature of my improvement is that the head or bodily movable portion of the bed is adapted to swing upward at an angle to the horizontal while the bed is extended and provided with supports by which it may be secured in an inclined position where it is desired to raise the head of the person occupying the bed. Finally my invention relates to an arrangement of a

spring whereby the manipulation of the article in opening and closing it is assisted.

In the accompanying drawings I have shown and in the following specification described a preferred form of my invention. It will be understood, however, that the detailed description is for the purpose of exemplification only and that the scope of the invention is set forth in the following claims in which I have endeavored to distinguish it from the prior art so far as known to me without, however, abandoning or relinquishing any part or portion thereof.

In the accompanying drawings Figure 1 is a front elevation of an article of furniture embodying my invention; Fig. 2 a longitudinal section through the furniture upon the line 2—2 of Fig. 1 showing certain parts thereof in elevation, the article being shown in both views in a closed position in which it forms a chair or settee; Fig. 3 is a similar view to Fig. 2 showing the article of furniture extended in the position which it occupies when used as a bed and in dotted lines the position which the bodily movable frame occupies when it is desired to elevate the head of the person occupying the bed; Fig. 4 is a partial plan.

The same character of reference is applied to each part throughout the several views.

The stationary frame is in the main like that of the furniture disclosed in my patent referred to above consisting in a pair of substantially L-shaped side frames formed preferably of L-irons and each including a lower horizontal rod 6, an upper horizontal rod 7, a front corner post 8, a vertical brace 9 and a rod or beam 10 bent intermediate its ends as shown at 11, 12 to form a rear corner post 13 and a slightly inclined frame member 15 secured to the upper and lower horizontal members respectively and against which the swinging frame rests when the article of furniture is in closed position. The side frames each comprise also an inclined brace 16 of L-metal which forms a guide for the rear end of the bodily movable bed frame as will be presently described. The side frames are connected together by rear cross braces 17 and struts 18 and 19 connected at their opposite ends respectively to the vertical braces 9. An angle iron 20 connects the upper rear corners of the side frames so that the stationary frame forms a rigid thoroughly braced structure. At each of its lower corners the frame is pro-

vided with a bracket 21 to form a bearing for a caster 22.

The swinging frame comprises a bed support 23 formed of a pair of parallel side pieces 24 bent upward at their free outer ends 25 and connected by a cross piece 26 shown in dotted lines in Fig. 3 which forms a foot piece for the bed when the article is extended. When the article is closed or collapsed the side members 24 rest against the inclined members 15 of the stationary frame and the foot piece 26 forms the top of the chair back. The stationary frame is provided at opposite sides with bracket plates 27 secured just within the side frames thereof to cross braces 18, 19 and provided with perforated ears 28, 29. In the lower ears 29 are bolts or pivots 30 upon which the elbow irons 31 are pivoted, such irons being bent and braced at 32 and connected at their forward or upper ends 33 to the side rails 24. A strut or brace 34 maintains each elbow iron 31 rigidly in its angular relation to its side rail 24, said brace being connected at 25 its respective ends to said elbow irons and rail for this purpose. There is thus formed a rigid structure extending from the pivots 29 by which it is secured to the stationary frame and including the elbow irons 31, the 30 side rails 24, the foot cross piece 26 and the brace 34. In order to more thoroughly brace and secure the swinging frame I connect the elbow members 31 by a sheet metal plate 35, shown in dotted lines in Fig. 2, and which is bent at its upper end 36 to form a rib and at its forward edge, speaking with reference to Figs. 1 and 2, is bent to conform to the angles of the elbows and to form an apron 37, the ends of which are extended at 38 along the short arms 39 of said elbow members. By reason of this bent cross plate the swinging member is given an ample degree of stiffness and rigidity for the purpose. The braces 34 when the bed is extended, are 40 in a substantially vertical plane and adjacent their upper ends the intermediate frame is pivoted to the side rails 24.

Tension springs 23' are connected at one end to the bracket ear 28 upon the stationary frame and at the other end to the swinging frame, their function being to assist in raising the swinging frame from the horizontal position and also to assist in moving it from the stationary frame when it is desired to 50 unfold the article of furniture to make a bed, the spring thus assisting the operator at the only two points in the operation of the bed where any considerable effort is required.

Said intermediate frame comprises rectangular end plates 40 pivoted at 41 to the side rails 24 and connected at their lower corners by cross angle irons 42, 43, the ends of which are bent up and secured along the edges of plates 40 shown at 43', Fig. 3. 55 There is thus formed an open box-shaped

frame, the top and sides of which are open except in the respect hereinafter mentioned and the front edges of which rest at 44 against the vertical struts or braces 34 when the furniture is in the extended position 70 whereby said intermediate frame is maintained horizontal. To the rear upper corners of the side plates 41 at 45' are pivoted the side rails of the bodily movable frame 45, the rear ends of said side rails being 75 connected by a cross rail 46, all of such rails being preferably formed of angle irons. Said side rails carry at their rear ends and upon the outer faces thereof rollers 47 which run upon the tracks 16 upon the stationary frame before mentioned and when the furniture is opened to form a bed, rest upon angle iron cross pieces 48 by which the rear end of said bodily movable frame is supported. 80

It will now be seen that with the parts in 85 the position shown in Fig. 3 the intermediate frame 40 is maintained in substantially horizontal position by reason of the fact that its front edges rest at 44 against the braces 34 of the swinging frame and the bodily movable frame is maintained in the horizontal position, being supported at its front end by the intermediate frame as above described and at its rear end by the rollers 47 resting upon the stop plates 48. 95

The forward end or foot of the swinging frame when lowered is supported upon the seat member which is so pivoted thereto that when the bed is extended it may be swung forward to engage the swinging frame near the front end or foot thereof and when the swinging frame is folded back against the stationary frame the seat member swings backward and rests upon the upper horizontal bars 7 of the stationary frame. The seat member comprises a pair of side frames and transverse members connecting the two. The side frames are each formed of a single strap or flat bar of metal, one end 50 of each of which forms the sides of the seat supporting frame. At each end of this flat horizontal portion of the strap it is riveted to the transverse angle irons 51, the rectangular frame so formed supporting the box or other seat 100 52 which may be of any ordinary or approved design. The strap is sharply bent about the rear transverse piece 51 to form an upwardly extending but slightly inclined rear section 53, at the upper end of which the strap is curved and forwardly bent as at 105 54 to form the top of the arm portion of the seat member. At 55 the metal strip is bent downwardly and extended past the front transverse bar 51 to form a leg 56, the arm forming strip being suitably riveted to the 110 transverse member 51 to form a rigid construction. As shown in Fig. 1, the leg 56 is somewhat broader than the forward edge of the side frame which it overlies. The inwardly projecting portion of the leg, that is 115 120 125 130

to say the part which does not overlie the edge of the stationary frame when the construction is folded to form a seat is somewhat extended and preferably turned as at 5 57 to form a foot which will not mar the floor or carpet upon which it rests when the furniture is in extended position. If desired the arm member may be provided with the cross braces 58, 59 to give it greater 10 rigidity.

I prefer to hinge the seat section to the side rails of the swinging frame by securing brackets 60 thereto, such brackets consisting of flat metal plates riveted to the 15 rails and curved as shown to project through longitudinal slots formed in the strap of the arm member at the upper rear corners thereof. Braces 61 are secured across the inner angles of the arm members at this 20 point and formed with perforations which register with similar perforations in the hinged brackets 60 and receive pivots 62. In this construction the seat member is so pivoted to the swinging frame that it may 25 take the relative position with reference thereto, shown in Fig. 2 to form a seat or be swung forward to the position shown in Fig. 3 to form a support for the foot of the bed. While the particular form of seat 30 member and the method of hinging it to the swinging frame are not essential to my invention in its broader aspect, they are especially well adapted for the purpose and form features of the invention in its more 35 restricted aspect.

The bodily movable frame 45 has hinged thereto at its rear end a sheet metal panel 63, there preferably being three hinges between the parts, the central one 64 of which is provided with a spring which tends to throw the panel 63 rearwardly so that it rests against the guides 16, thus forming an abutment to maintain the pillow and mattress against any tendency to be displaced rearwardly. The panel 63 is provided near its 40 rear edge with a pair of bolts 65 which may be spring-biased if desired, to enter openings 66 formed in the inclined members 15 whereby the rear end of the bodily movable 45 frame may be sustained in adjusted inclined position. It will of course be understood that the horizontal portion of the swinging frame (speaking with reference to the 50 opened position of the furniture as seen in Fig. 3), the intermediate frame and the bodily movable frame are provided with suitable transverse supports for a mattress, such as the spring mattress 67 shown in Fig. 4. This spring mattress may be continuous 55 throughout the several frames or each such frame may be separately provided therewith.

In order to more rigidly hold the seat member upon the horizontal rails 7 of the stationary frame when the furniture is in 60 its folded or collapsed position, I form said

horizontal rails of the stationary frame with slotted or cutout portions 68 into and through which extend tongues 69 secured to the under side of the side members of the seat frame. Thus, when the furniture is in 65 closed position with the just described parts in interlocking engagement, the swinging frame cannot be tilted forward without raising the seat, thus greatly adding to the rigidity of the structure. In order to avoid 70 accidental raising of the seat a bail 70 is pivoted thereto at 71, 72, which bail is formed with a handle portion and depressed portions 73, 73 adapted to engage spring hooks 74, 74 secured upon the inclined brace 80 plate 85 upon the swinging frame. In order to unfold or extend the furniture to form a bed, it is only necessary to grasp the bail by the intermediate handle portion and draw it forwardly and upwardly, whereby 85 the seat is released and raised whereupon the further forward motion of the bail causes the swinging frame to tilt forwardly and finally to reach the extended position. In the meantime the operator maintains his 90 hold upon the bail, drawing the same forward thereby causing the seat section to swing forward into the position shown in Fig. 3 in which it supports the foot of the bed. When the bed is to be folded to 95 restore the article of furniture to the condition in which it acts as a seat, the action is reversed. The bail is grasped and raised until the swinging frame reaches the position in which the springs tend to close the same. 100

During this initial movement the bodily movable section folds upward and is followed by the intermediate section which assumes an angle with relation to the plane of the swinging frame. During this movement 105 also the seat member swings downwardly with reference to the swinging frame and as the folding movement of the swinging frame is completed the seat member finally assumes the position shown in Fig. 2 of the 110 drawings.

If desired an apron 76 may be hung from the forward edge of the seat frame so as to hide the bail and associated parts beneath the seat. Preferably also a curtain 77 may 115 be hung to the rear of the stationary frame to improve the appearance thereof.

The article of furniture may be upholstered in any desired manner so as to completely conceal the structure of the chair 120 and to present substantially the appearance of a solid piece of furniture. That face of the swinging frame which is exposed when the furniture is closed and forms a support for the back of the person occupying the 125 seat is or may be cushioned and covered with any suitable upholstery material such as leather or the like which extends up over the foot of the bed, which as before stated when the article is closed extends over the 130

top of the stationary frame. The outer or exposed faces of the side members of the stationary frame are also preferably covered with upholstery material and suitably 5 padded.

My article of furniture when made as above described in the closed position has all the appearance of a piece of furniture of permanent shape and is rigid and of presentable appearance. When extended it forms a firm support for a bed or mattress which may be either loosely applied thereto or so tied to the bed supporting frames as to be folded therewith into the back of the 15 seat when the article is in the condition shown in Fig. 2.

I claim:

1. In an article of furniture of the class described, a stationary frame comprising 20 side members, a swinging frame pivoted to said stationary frame and comprising a mattress supporting section adapted to assume a substantially horizontal position and to be folded into a substantially upright position, 25 a seat member movably connected to the swinging frame and adapted to form a seat when the latter is swung into closed position and to form a support for the same when in its horizontal position.

30 2. In an article of furniture of the class described, a relatively stationary frame, a swinging frame pivoted thereto and adapted to swing into horizontal position and into a raised position against the stationary frame, 35 and a seat member pivoted to the swinging frame intermediate the ends of the latter and adapted to swing outwardly beneath the free end of the swinging frame when the latter is in horizontal position to 40 support the same and to swing inward against said swinging frame to form a seat therewith when the latter is in raised position.

3. In an article of furniture of the class 45 described, a stationary frame comprising side members, a swinging frame pivoted to said stationary frame and having a mattress supporting section adapted to assume a substantially horizontal and a substantially vertical position, a seat member comprising a seat proper and a pair of arms thereon and a pivotal connection between said seat member and swinging frame such that the latter may rest upon the arms of the 55 seat member when the swinging frame is in horizontal position and the seat member may swing against the frame to form a seat when said frame is folded.

4. In an article of furniture of the class 60 described, a stationary frame comprising side members, a swinging frame having a mattress supporting section pivoted on the stationary frame and adapted to swing into substantially horizontal position and into 65 substantially upright position, a seat member

comprising arms extending upwardly at the sides thereof, a pivotal connection between the seat member and the swinging frame such that the latter extends over and rests upon said arms when in lowered position.

70

5. In an article of furniture of the class described, a stationary frame comprising side members, a swinging frame pivoted to the stationary frame and comprising a bed section adapted to assume a substantially horizontal position, a seat member pivoted to the swinging frame and adapted when the latter is in a substantially horizontal position to assume a substantially horizontal position and support said frame and when the 80 swinging frame is in its upright position to assume a substantially horizontal position on the stationary frame.

6. In an article of furniture of the class described, a stationary frame comprising a 85 pair of side members rigidly connected together, a swinging frame pivoted to said stationary frame and comprising a bed section adapted to assume a substantially horizontal position and a substantially upright position, a seat member comprising a seat proper, an upward extension thereof pivoted to the swinging member and adapted to form a support for the latter when it is in substantially horizontal position, said seat member 95 further being adapted to be supported by the stationary frame when the swinging frame is in closed position.

7. In an article of furniture of the class described, a stationary frame comprising 100 side members each having an upright portion and a substantially horizontal portion, rigid connections between said side members, a swinging frame comprising a bed supporting section adapted to assume a substantially 105 horizontal position and to close against the front edges of said side frames and a seat member pivoted to said swinging frame and adapted to swing outwardly under the free end of the latter to form a support therefor 110 and to rest upon the horizontal portions of said side members.

8. In an article of furniture of the class described, a relatively stationary frame having a substantially upright and a substantially horizontal portion, a swinging frame pivoted to the horizontal portion of said stationary frame and adapted to swing downwardly into a horizontal position to support a mattress and upwardly to rest 120 against the upright portion of the stationary frame, a swinging seat member pivoted to the swinging frame intermediate the ends of the latter and adapted to swing outward to support the free end of said swinging frame when in horizontal position and inward to rest upon the horizontal portion of the stationary frame when the swinging frame is raised.

9. In an article of furniture of the class 130

described, a stationary frame comprising a pair of side members rigidly secured together, a swinging frame pivoted to said stationary frame and adapted to assume a horizontal position and an upright position, a seat member pivoted to said frame and adapted to swing outwardly beneath the latter to form a seat therefor when in extended position and floor-engaging supports for the seat member at the front and rear thereof.

10. In an article of furniture of the class described, a stationary frame comprising an upright and a horizontal portion, a swinging frame pivoted to the horizontal portion and adapted to swing into horizontal position for supporting a mattress or into folded position against the stationary frame, as desired, a seat member comprising a seat, a pair of legs and arm sections, pivoted to the swinging frame intermediate its ends and adapted to swing outwardly under the swinging frame into such a position that the arms of the seat member support the free end of the swinging frame, said seat member also adapted to swing downwardly with respect to the swinging frame when the latter is raised and to rest upon the horizontal portion of the stationary frame.

11. In an article of furniture of the class described, a relatively stationary frame having an upright and a horizontal portion, a swinging frame pivoted to the horizontal portion of the stationary frame and adapted to swing downwardly into a horizontal position or upwardly against the upright portion of the stationary frame, a seat member comprising a seat frame, a pair of side arms each comprising an upright rear member and a substantially horizontal member, said seat member pivoted to the swinging frame intermediate the ends of the latter and adapted to swing forwardly thereunder so that the horizontal portions of the arms form a support for the free end of the swinging frame and also adapted to swing rearwardly when the swinging frame is raised or folded so that the seat rests upon the horizontal portion of the stationary frame.

12. In an article of furniture of the class described, a stationary frame comprising an upright portion and a horizontal portion, a swinging frame pivoted to the horizontal portion and adapted to swing downwardly into a horizontal position and upwardly into a position against the upright member of the stationary frame, a pair of bracket plates secured to the swinging frame intermediate its ends, a seat member comprising a pair of arms, said arms being slotted near their upper rear corners to receive the bracket plates and pivots connecting the bracket plates and said arms whereby the seat member can swing forwardly under the free end of the swinging frame to support the same when the frame is lowered and rearwardly

to abut against said frame and the horizontal portion of the stationary frame when the swinging frame is elevated.

13. In an article of furniture of the class described, a stationary frame comprising an upright and a horizontal portion, a swinging frame comprising a mattress supporting section and elbows rigidly connected to said mattress supporting section, said elbows being pivoted to the stationary frame near the lower front corners thereof, a plate extending between and bracing said elbows, a seat member pivoted to the swinging frame intermediate its ends and adapted to support the same when lowered, an intermediate mattress supporting section and a bodily movable mattress supporting section pivoted to the intermediate mattress supporting section whereby when the swinging frame is raised the intermediate section is forced rearwardly and the bodily movable section forced rearwardly and turned upwardly into a vertical position.

14. In an article of furniture of the class described, a stationary frame having a horizontal and an upright portion, a swinging frame pivoted to said stationary frame and adapted to swing into a horizontal mattress supporting position and into a position in contact with the upright portion of the stationary frame, a seat member pivoted to the swinging frame intermediate its ends and adapted to swing forward under the free end of the swinging frame to support the latter when in horizontal position and to swing backward against said swinging frame and to rest upon the horizontal portion of the stationary frame to form a seat, lugs upon the bottom of the seat member and openings in the stationary frame to receive said lugs whereby the seat when the article is in closed position locks the swinging frame against the stationary frame.

15. In an article of furniture of the class described, a stationary frame comprising a pair of side members, a swinging frame pivoted to the stationary frame and adapted to swing into a horizontal position and into a substantially vertical position, a seat member pivoted to the swinging frame and adapted to swing forwardly under the free end of the swinging frame to support the latter when in horizontal position, lugs upon the bottom of said seat member having cammed forward edges and openings in the stationary frame to receive said lugs whereby the seat when the article is in closed position forms a brace to maintain said swinging frame against the stationary frame.

16. In an article of furniture of the class described, a stationary frame having a horizontal and an upright portion, a swinging frame pivoted to said stationary frame and adapted to swing into a horizontal mattress supporting position and into a position in

6

contact with the upright portion of said stationary frame, a seat member pivoted to the swinging frame and adapted to swing forward under the free end of the swinging frame to support the latter when in horizontal position and to swing backward against said swinging frame, lugs upon the bottom of the seat member and holes intermediate the side edges of the frame members and adapted to be entered by said lugs whereby said seat member forms a lateral brace for the stationary frame when in closed position.

17. In an article of furniture of the class described, a stationary frame comprising a horizontal and an upright portion, a swinging frame pivoted to the front lower portion of the stationary frame and adapted to be swung downwardly to a horizontal position to support a mattress and upwardly in a folded position against the stationary frame, a seat member pivoted to the swinging member intermediate the ends thereof and adapted to swing forward when the swinging frame is lowered to support the free end of the latter and rearward when the swinging frame is raised to a position to brace the swinging frame against the stationary frame, means on the seat member for maintaining it in the last-named position, and a catch for preventing the raising of the seat member until detached.

18. In an article of furniture of the class described, a stationary frame, a swinging frame pivoted thereto and adapted to be lowered into substantially horizontal position, an intermediate section pivoted to the swinging frame and supported in horizontal position when the latter is lowered, a bodily movable frame pivoted to the rear end of the intermediate frame and a panel pivotally attached to the end of the bodily movable frame.

19. In an article of furniture of the class described, a stationary frame, a swinging frame pivoted thereto and adapted to be lowered into substantially horizontal position, an intermediate section pivoted to the swinging frame and supported in horizontal position when the latter is lowered, a bodily movable frame pivoted to the rear end of the intermediate frame, a panel pivotally attached to the end of the bodily movable frame, and means upon the panel for adjustably supporting it in an inclined position.

20. In an article of furniture of the class described, a stationary frame, a swinging frame pivoted thereto, an intermediate section supported by the swinging frame, a bodily movable section hinged at one end to the intermediate frame and free at the other end, a support for the free end of the bodily movable frame for maintaining the same in horizontal position when the article of furniture is extended to form a bed, and adjustable means for maintaining the bodily movable frame in inclined position.

21. In an article of furniture of the class described, a stationary frame comprising a pair of side frames, a swinging frame comprising a bed supporting section adapted to assume a substantially upright and a horizontal position, elbow members rigidly secured to said swinging frame and pivoted near the front lower corners of the side members of the stationary frame, and a bent plate connecting said elbow members and adapted when in closed position to form a panel upon the front of the article of furniture.

ALEXANDER D. ELLIOTT.
